SHOELACE HOLDING DEVICE

Albert W. H. Hirsch, Tampa, Fla.

Application June 25, 1940, Serial No. 342,388

5 Claims. (Cl. 24—121)

This invention relates to a shoelace holding device.

An object of the invention is the construction of a simple and efficient device for quickly and securely locking or fastening shoelaces particularly, or any other laces such as draw strings on bags, laces in clothing, leather goods, etc.

Another object of the invention is the construction of a device including a casing through which the ends of a lace are threaded, this casing being provided with manually-operated means for engaging portions of the shoelace and normally holding same against movement, whereby the object upon which the lace is mounted will be retained in a closed position.

With the foregoing and other objects in view, the invention comprises certain novel constructions, combinations, and arrangements of parts as will be hereinafter fully described, illustrated in the accompanying drawing, and more particularly pointed out in the appended claims.

In the drawing:

Figure 1 is a view in front elevation of a device constructed in accordance with the present invention, showing the same applied to a lace, while 25

Figure 2 is a top plan view of same.

Figure 3 is an enlarged sectional view taken on line 3—3, Fig. 1 and looking in the direction of the arrows.

Figure 4 is a sectional view taken on line 4—4, 30 Fig. 3 and looking in the direction of the arrows.

Figure 5 is an enlarged top plan view of another embodiment of the present invention, while

Figure 6 is a front view of the same.

Figure 7 is a sectional view taken on line 7—7, 35 Figure 6 and looking in the direction of the arrows.

Figure 8 is a sectional view taken on line 8—8, Figure 7 and looking in the direction of the arrows.

Referring to the drawing, in which I have shown the preferred embodiments of my invention, 1 designates a casing, preferably made of metal, which casing is provided in its outer end with an aperture 2, and its inner end is entirely open. In the sides of casing 1, and near its inner end are registering apertures 3, through which portions of the lace 4 are adapted to be threaded, so that the lace will extend as clearly shown in Figure 3. Slidably mounted in aperture 2 is 50 a plunger pin 5 that has on its outer end a grip 6, and on its inner end a bevelled-edge head 7. The bevelled-edge of head 7 normally presses or clamps tightly upon portions of the lace 4. A coil spring 8 is placed around plunger pin 3, with

the inner end of the spring pressing upon head 7 and its outer end pressing upon the closed outer end of casing 1.

The lace 4 is threaded through eyes 9, which 5 eyes are mounted upon the shoe or garment that is to be closed by the lace; my device will efficiently operate on any kind of a garment where a lace is employed. Further, I use the term "lace" in a broad sense, meaning any kind of a shoe lace or a string or a like device.

The head 7 has its bevelled edge preferably roughened (Figs. 3 and 4), so as to assist in efficiently holding the lace from slipping or creeping when the head 7 is clamping or pressing upon 15 same.

In the embodiment shown in Figures 5 to 8 a casing 10 is employed which is preferably cylindrical shape. In this casing 10 is a filler 11, which is cut away at 12, Fig. 8, producing a compartment 13 in the casing 10. The filler 11 and casing 10 are provided with registering apertures 14, and casing 10 is also provided with apertures 14a, registering with said apertures 14. The lace 4 is threaded through apertures 14 and 14a as is clearly shown in Figure 7. A flat clamping spring 15 is fastened by screw 16 to the filler 11 within compartment 13. The ends of spring 15 clamp upon portions of lace 4, performing the same function as head 7 in the embodiment shown in Figures 1 to 4. The casing 10 is provided with apertures 17 (Fig. 7) through which extends a flexible connector 18; the ends of connector 18 are fastened at 19 to the flat clamping spring 15. A grip 20 is on the flexible connector 18, outside of casing 10. Therefore, when the operator grasps grip 20 and pulls outwardly, as shown in dotted line in Figure 7, clamping pressure will be removed off the lace 4, so that it can be threaded freely through the device. Upon the operator releasing grip 20, the spring will immediately clamp the lace, holding it against accidental slipping or sliding.

In the embodiments the common features are the yielding clamping means, engaging the lace, and the sliding manually-operated means that extends through the top of the casing and connected to the yielding clamping means, whereby the clamping pressure upon the lace can be removed, by operator manipulating the device.

It is to be understood that as a time-saver, the device will perform a service to all who wear lace shoes, and in many other cases where laces are used to close or fasten wearing apparel, bags, containers, etc. The customary procedure for tying shoelaces, for example, consists of first

making an ordinary knot and then a bow, requiring a minimum of six separate movements or operations. The laces, by means of my invention, may be fastened to any degree of tightness in one quick pull on the lace ends. Only one operation is also required in the reverse process of unfastening. The device also possesses many other features of convenience, safety, simplicity, comfort and beauty.

While I have described the preferred embodiments of my invention and illustrated same in the accompanying drawing, certain changes or alterations may appear to one skilled in the art to which this invention relates during the extensive manufacture of same, and I, therefore, reserve the right to make such changes or alterations as shall fairly fall within the scope of the appended claims.

What I claim is:

1. In a device of the class described, the combination of a casing provided at opposite portions with lace receiving means, a yieldable clamping unit in said casing and positioned between said opposite portions, and means provided with a grip outside of said casing and being connected to said yieldable clamping unit, whereby said unit can be operated by the operator.

2. In a device of the class described, the combination of a casing opened at its inner end and closed at its outer end, said outer end provided with an aperture, a plunger pin slidably mounted in said aperture, said casing provided near the open inner end with a pair of registering apertures, a bevelled clamping head in said casing contiguous to said registering apertures and fastened to said plunger pin, a coil spring on said plunger pin having one end bearing against said

head and its other head bearing against the outer end of said casing, and a grip on said plunger pin outside of said casing.

3. In a device of the class described, the combination of a casing provided with means for threading portions of a lace therethrough, a clamping spring in said casing and being adapted to engage portions of a lace when threaded through said casing, and a manually-operated means connected to said clamping spring.

4. In a device of the class described, the combination of a casing, a filler in said casing, said casing and filler provided with lace-receiving apertures, a flat spring fastened to said filler and having portions in the line of movement of a lace passing through said lace-receiving apertures, and yieldable operated means extending through portions of said casing and securely fastened to said flat spring.

5. In a device of the class described the combination of a cylindrical-like casing, an elongated filler in said casing, said filler being cut away at its center, said casing and filler provided with registering lace receiving apertures, a flat spring fastened at its center through part of the cut-away portion of said filler, said flat spring having its ends extending to said registering apertures, whereby said ends will press upon portions of the lace threaded through said apertures, a flexible connector slidably mounted upon portions of said casing, said connector having its ends fixedly secured to said flat spring, and a grip outside of said casing and mounted upon said flexible connector.

ALBERT W. H. HIRSCH.
